APPARATUS FOR RECLAIMING ORE AND
THE LIKE FROM STORAGE PILESMorris J. Andrada, Brooklyn, N. Y., assignor to
Robins Conveying Belt Company, Passaic,
N. J., a corporation of New Jersey

Application October 8, 1938, Serial No. 233,961

6 Claims. (Cl. 198—36)

This invention relates to apparatus for reclaiming granular material from storage piles, having reference more especially to the reclaiming of ore which is bedded or stocked in laminations so that an assay of any cross-section through a pile is representative of the average assay of the entire pile.

In a type of reclaiming system heretofore employed transfer conveyors were arranged longitudinally of and in alternation with a plurality of elongated substantially parallel piles of material, each conveyor extending from end to end of its adjacent pile and receiving the material which was progressively removed from the pile. Such conveyor, in turn, carried the imposed load to conveyors for transporting the material to the furnace or smelter plant. The mechanism for thus reclaiming the material was mounted and arranged to travel longitudinally of and from end to end of any predetermined stock pile. Such mechanism embodied an associated harrow and an endless plow conveyor, the former having capacity for up and down movement in relation to the opposing transverse face of the pile and being effective to cut a complete cross-section from the pile and deliver the separated material to the plow conveyor, and the latter, in turn, delivering such material to the transfer conveyor. The travel of the active run of the plow conveyor was in one direction only, namely, toward the adjacent transfer conveyor, and the plows were curved or hook-shaped on one side to accord with such direction of travel, thus necessitating for each individual stock pile a separate transfer conveyor and operating mechanism therefor.

According to my invention the use of a separate transfer conveyor for each individual stock pile is avoided, but instead only one half of the number of transfer conveyors for the total number of piles is required, thus materially reducing the initial and operating costs of the system.

To this end my invention provides a reclaiming mechanism which is operative to transfer the separated material from either of two adjacent piles to a single transfer element, or trench conveyor, located therebetween, which mechanism comprises novel features of construction and combinations of parts which will be herein-after described and claimed.

In the drawings—

Figure 1 is a diagram of a storage floor equipped with a form of reclaiming apparatus embodying my invention.

Fig. 2 is a longitudinal vertical section through

the floor and appurtenances, as on the line 2—2 of Fig. 1, showing the reclaiming apparatus in front elevation.

Fig. 3 is a similar section through one of the storage areas, as on the line 3—3 of Fig. 1. 5

Fig. 4 is a partial plan of the reclaiming apparatus.

Fig. 5 is a section taken at right angles to Fig. 2 through one of the storage areas, as on the line 5—5 of Fig. 1. 10

Figs. 6 and 7 are a plan and a side elevation, respectively, of a portion of the endless plow conveyor.

Fig. 8 is a transverse vertical section through the plow conveyor, as on the line 8—8 of Fig. 7. 15

Fig. 9 is a sectional elevation of one of the plows, the section being taken through one of the lateral plow points, as on the line 9—9 of Fig. 8, the tapering and flared portion of which point is indicated by broken lines. 20

Fig. 10 is a bottom view of a portion of a plow blade, whereof the points are indicated by broken lines.

Fig. 11 is a side elevation of one of the plow points, looking at the inner or locking face of 25 the point.

Referring to the drawings, 15 designates an elongated storage floor of generally rectangular formation upon and throughout which laminated stock piles P are bedded in spaced parallel relation or substantially so. The material is subsequently reclaimed from each of the piles as need may require. The piles are arranged in succeeding pairs, as seen in Fig. 1, and in the floor space between the piles of each pair is a 30 transverse trench 16 within and longitudinally of which is mounted load transfer means comprising preferably an endless conveyor belt 17. This belt passes about pulleys 18 supported on shafts 19 at the respective sides of the storage 35 floor. One of the pulleys 18 overhangs suitable off-bearing means also comprising preferably a belt conveyor 20 which extends longitudinally of the adjacent side of the floor and leads to a determined location, the upper or receiving end 40 of the conveyor 17 being driven toward the conveyor 20 in any suitable manner. Hence material removed from either pile of a pair and deposited upon the intervening conveyor 17 will be delivered thereby to the conveyor 20 for transportation to a furnace or smelter plant, for example. 45

Each of the trenches 16 for the transfer conveyor 17 is provided with a longitudinal supporting structure 21 for rails 22 to which are adapted 50

the wheels of a truck 23 carrying a hopper 24 which overhangs the upper run of such conveyor and is located to direct thereto the material discharged from the plow conveyor.

5 The storage area for each stock pile is flanked by a pair of rails 25 which extend from the front to, or nearly to, the rear of the floor. Arranged along and parallel with the front of the floor is a sunken trackway 26 upon which is mounted a 10 wheeled truck 27 that may be pushed along such trackway to a position in front of the adjacent end of any stock pile, as desired. The top of the floor 28 of the truck is flush with the storage floor, or substantially so, and is equipped with 15 a pair of transverse rails 29 adapted to align with and constitute, in effect, a continuation of the rails 25 which flank the selected pile in front of which the truck may be positioned.

The rails 29 are adapted to receive and support 20 the wheels 30 of a reclaimer car C embodying a body 31 having suitably-arranged axles 32 for the wheels 30, and hence when the transfer truck is positioned with its rails 29 in alignment with the rails 25 of any selected pile, the reclaimer car can 25 be moved rearwardly upon and along the latter rails and can thereafter be retracted and positioned on the rails of the transfer truck preparatory to the setting of the latter adjacent any of the other piles on the storage floor, as indicated 30 by dotted lines at the right of Figs. 1 and 2.

The mechanism illustrated for actuating the reclaimer car is as follows: The axles of each pair of rearward wheels 30 are provided with worm wheels 33 with which mesh worms 34 fast 35 on crossshafts 35 having suitably located bearings that are affixed to the car structure. Each of the shafts 35 is connected by co-acting bevel gearing 36 with the respective ends of a suitably located shaft 37 which extends longitudinally of 40 the structure. Mounted on the car are two independently operable electric motors 38 and 39, respectively, which are connected by means of suitable gearing 40 and 41 with the shaft 37. The motor 38, which is equipped with a variable speed 45 unit 42, is operable to rotate the shaft 37 in one direction to effect through the described transmission gearing the rearward travel of the car C toward the opposing pile, and the motor 39 is operable to impel the car at a relatively high speed in either direction.

50 Mounted on the rearward side of the reclaimer car and extending longitudinally thereof, is an endless chain conveyor 43 which passes about sprocket wheels 44 arranged on shafts 45 at the 55 respective ends of the car. The shaft 45 at one end of the car has an extension 46 which is connected by suitable gearing 47 with the shaft 48 of a reversible electric motor 49 which is supported on the floor of the car. Hence by proper 60 operation of the motor 49 the chain conveyor 43 can be driven in either direction longitudinally of the car structure. The chain is equipped throughout its length with a continuous series of spaced plows of special construction which are 65 arranged and adapted to traverse the adjacent storage floor during the travel of the chain in either direction transversely of the stock pile. Each of the plows and its connection with the chain are of the following description:

70 50 designates a T-shaped element whereof the head comprises a plate member 51 having midway of its ends side flanges 52 which are supported on the sides of the adjacent inner link of the chain by means of a removable pivot pin 53. The sides 75 of the member 51 have bolted thereto at its ends

angle pieces 54 having guide lugs 55 which are arranged to travel in longitudinal guide-ways formed by parallel bars 56 fixed on the rearward side of the car body. The bars terminate adjacent the respective sprocket wheels 44, and serve to guide and limit the T-member in its pivotal movement in relation to the chain during the flexure of the chain as it rounds the sprocket wheels at the ends of the car.

The outwardly extending member 57 of the 10 T-element constitutes a plow blade having its lower portion extended forwardly and rearwardly beyond the respective sides of the chain, as at 58 and 59, respectively. The lower and forward edges of the blade are laterally expanded, as at 60 15 and 61, respectively, thence curved inwardly to the respective sides of the blade to present a smooth deflecting surface for the material which is subjected to the action of the blade in its travel adjacent the storage floor.

The lower outward portion of the rearward extension 59 of each of the blades is laterally reduced to provide a substantially triangular supporting web 62, to the respective sides of which are detachably bolted oppositely acting plow 20 points 63, which are laterally interlocked with the opposing faces of the web by suitably arranged mating projections 64 and sockets 65. In the present instance the plow point is provided with two projections and one socket, and each face of 25 the web is provided with two sockets and one projection, the projections and sockets of the respective members being arranged in interlocking relation, and having suitable holes for the passage of 30 the connecting bolts.

The plow points have nose portions 66 which extend somewhat beyond the plane of the outer longitudinal edge of the adjacent blade. These noses flare laterally, as at 67, thence gradually tapering to the respective faces of the body of the 35 point, which faces merge with the outer faces of the blade. Thus during the travel of the lower run of the chain belt to the adjacent trench conveyor 17 the acting plow point effectively attacks the material opposed thereto and forces it progressively toward and against the leading face of 40 the blade for advancement thereby to such conveyor in a smooth and easy manner, and this irrespective of the direction of travel of the plow conveyor as required by the location in respect to the 45 trench conveyor of the particular stored pile which is being reclaimed. The construction and contour of each of the plow points is clearly seen 50 in Figs. 6 to 11, inclusive.

It has been found by experience that a plow 55 having a hook-shaped point as heretofore constructed has a tendency to fill the compartment between the adjacent blades too early in its travel across the face of the pile; whereas a two-way plow of the construction herein described, fills 60 more gradually the compartment between adjacent plows, irrespective of their direction of movement, thus insuring a better specimen of the average assay in each compartment on the plow conveyor and resulting in the delivery to the 65 transfer conveyor of a stream of material of more uniform analysis than heretofore.

The reclaimer car C is equipped with an up-standing swinging harrow structure 68 which is pivoted at its lower end, as at 69, to the body of 70 the car. The upper end of the harrow is connected by a cable 70 with an electric hoist 71 which is mounted on a truss structure 72 erected on the car. By properly operating the hoist the harrow can be positioned upon and in proper rela- 75

tion to the opposing inclined face of the pile. One end of the structure is pivotally connected by means of a link 73 with a crank disk 74 fast on the adjacent shaft 45, whereby during the rearward travel of the reclaimer car and its appurtenances above the storage floor and in operative relation to the face of the pile, the harrow is agitated to attack the opposing material and separate it from the pile, which separated material thereupon gravitates to the storage floor and into the active path of the lower run of travelling double-faced plows irrespective of the direction of travel of the plows, as and for the purpose previously described.

15 I claim—

1. An apparatus for reclaiming ore or other granular material stored on a floor having a plurality of spaced storage areas arranged in pairs and having also transfer means in the space between the areas of each pair, said apparatus comprising a travelling structure movable adjacent and longitudinally of said floor and also movable thereover to traverse any selected storage area in front of which the structure may be positioned, means on said structure constructed and arranged to act upon and disturb the opposing material in any selected area during the rearward traverse of the structure upon said area, thus progressively separating such material and causing it to gravitate to the said area, an endless conveyer mounted and arranged on said structure for independent movement transversely of such selected area, spaced double-face plows carried by said conveyer so as to progress across said area, and means supported by said structure for actuating said conveyer to move the plows on the lower run thereof in one direction while they are acting upon the material of one area, and in the opposite direction when they are acting upon the material of the adjacent area, whereby such material in either case is delivered to the transfer means between and common to the two adjacent areas.

2. In an apparatus of the type described comprising a travelling structure having thereon an endless conveyer, a succession of spaced plows carried by said conveyer, and means for driving said conveyer to move its active run in either direction, as desired, each of said plows comprising a transverse blade member having at one end lateral members constituting plow points having oppositely-disposed acting faces which merge with the respective faces of the blade member.

3. In an apparatus of the type described comprising a travelling structure having thereon an endless conveyer, a succession of spaced plows carried by said conveyer, and means for driv-

ing said conveyer to move its active run in either direction, as desired, each of said plows comprising a transverse blade member having at one end lateral members constituting plow points having oppositely-disposed acting faces which merge with the respective faces of the blade member and also having laterally flared nose portions which project outwardly beyond the plane of the longitudinal edge of said blade member.

4. In an apparatus of the type described comprising a travelling structure having thereon an endless conveyer, a succession of spaced plows carried by said conveyer, and means for independently driving said conveyer to move its active run in either direction, as desired, each of said plows comprising a transverse blade member having a reduced corner portion constituting a web, and lateral members constituting plow points embracing said web and secured thereto, said plow points having oppositely-disposed acting faces which merge with the respective faces of the blade member.

5. In an apparatus of the type described comprising a travelling structure having thereon an endless conveyer, a succession of spaced plows carried by said conveyer, and means for independently driving said conveyer to move its active run in either direction, as desired, each of said plows comprising a transverse blade member having a reduced corner portion constituting a web, and lateral members constituting plow points embracing said web and secured thereto, said plow points having oppositely-disposed acting faces which merge with the respective faces of the web and the contiguous surfaces of said web and the respective plow points having interlocking sockets and projections.

6. In an apparatus of the type described comprising a travelling structure having thereon an endless conveyer, a succession of spaced plows carried by said conveyer, and means for independently driving said conveyer to move its active run in either direction, as desired, each of said plows comprising a transverse blade member having a reduced corner portion constituting a web, and lateral members constituting plow points embracing said web and secured thereto, said plow points having oppositely-disposed acting faces which merge with the respective faces of the web and having laterally flaring nose portions projecting outwardly beyond the plane of the longitudinal edge of the blade member, the contiguous surfaces of said web and the respective plow points having interlocking sockets and projections.

MORRIS J. ANDRADE.
